UNITED STATES PATENT OFFICE

ARTHUR H. LABISKY, OF WEST BEND, WISCONSIN, ASSIGNOR TO THE BARTON CORPORATION, OF WEST BEND, WISCONSIN, A CORPORATION OF WISCONSIN

DESIGN FOR A WASHING MACHINE TUB

Application filed January 18, 1932. Serial No. 42,531. Term of patent 14 years.

To all whom it may concern:

Be it known that I, ARTHUR H. LABISKY, a citizen of the United States, residing at West Bend, in the county of Washington and State of Wisconsin, have invented a new, original, and ornamental Design for a Washing Machine Tub, of which the following is a specification, reference being made to the accom-

panying drawing, forming a part thereof, in which the single figure is a perspective view showing a washing machine tub embodying my new design.

I claim:

The ornamental design for a washing machine tub as shown.

ARTHUR H. LABISKY.
